UNITED STATES PATENT OFFICE

EDWARD A. NIELE, OF PITTSBURGH, PENNSYLVANIA

INDICATOR DEVICE

Application filed February 28, 1929. Serial No. 343,344.

This invention relates to indicator devices, and more in particular to such devices intended to be used in connection with the headlights of automobiles and the like.

5 The primary object of this invention is to provide an indicator device which may be readily attached to the headlights of a vehicle and whereby the driver thereof may at all times ascertain whether or not said headlights 10 are burning. Another object of this invention is to provide an indicator device of this character which is entirely mechanical in its operation and which may be applied to headlights operating by electricity, gas or in any 15 other manner. Yet another object is to provide an indicating device of this character which is simple in construction, positive in operation, adjustable within practical limits to suit various sizes and types of headlights, 20 and which can be manufactured at relatively low cost. Additional features and advantages of this invention will appear in the course of the following description considered in connection with the accompanying drawings which forms a part of this application, 25 and in which:

Fig. 1 is a side elevation showing the application of my indicator device, partly in section, to a headlight of an automobile.

30 Fig. 2 is a front elevation of Fig. 1.

Fig. 3 is a side elevation, partly in section, of the preferred embodiment of my invention.

Fig. 4 is a front elevation of Fig. 3, and

Fig. 5 is a fragmentary view showing a 35 slightly modified construction of the indicator device.

Referring to the drawing, the indicator device comprises a reflector element 1 formed preferably integrally with an apron 2 suitably curved at the base 3 to seat on the outside of the housing 4 of the headlight 5. The reflector 1 is suitably curved and extends a sufficient amount within the field of light rays of the headlight to reflect some of the light rays back through a tell-tale lens 6 made of any suitable transparent material, preferably of glass colored to suit.

This lens is set within an enlargement 7 provided in a sleeve-member 8 inserted 40 through and secured to the apron 2, in any

desired manner, in proper alignment with the reflector 1. The sleeve-member has at its upper inner end a substantially semi-cylindrical cut-away portion, the purpose of which is to enable a greater number of light-rays to be reflected by the reflector toward the lens 6. Furthermore, the semi-cylindrical extension 9 serves to prevent light-rays from on-coming automobiles to shine through the lens and also to protect the inner face of the latter, to a certain extent, against splashing mud, etc.

The indicator is preferably made of sheet metal which may be readily bent by hand for adjustment purposes, such as for instance, to enable the reflector element to be bent forwardly to come within reach of some of the rays of light of the headlight, in the slightly inclined position shown in the drawing. Another object of inclining the indicator is to bring the axis of the lens 6 more in line with the line of vision of the driver of the automobile. The interior face of the reflector element is, of course, suitably polished and covered with a reflecting coating, such as nickel plating, etc., to improve its reflective properties.

The indicator device may be secured to a headlight in any desired manner, such as by riveting, soldering, or welding; these methods are especially appropriate when the device is originally applied by the manufacturer of the headlight. However, when the indicator device is to be applied by individual owners of automobiles, I prefer to supply each device with a pair of flexible and easily bendable clamping strips 10, in each of which a series of holes 11 are provided for the insertion of a clamping-bolt 12, having nuts 13, by means of which the indicator may be clamped about the housing of the headlight, in the manner shown in the drawing.

These clamping strips are made long enough to accommodate the larger sizes of headlights and, when applied to small headlights, the excess length of these strips may be easily cut away with shears, as will be readily understood.

The modification shown in Fig. 5 differs from the embodiment above described in that

the reflector element 1 is provided with lateral shields 14, which prevent any light-rays from passing vehicles to shine through the indicator lens; which also stiffens the whole reflector against deformation and to a great extent protects the inside of the lens against splashing mud, rain, etc.

The indicator device shown in the drawing is applied to a headlight by first spreading the clamping strips 10, sufficiently apart to pass over the ring 15 which holds the glass 16 of the headlight. These clamping-strips are now bolted together tight on the headlight, and the indicator is then suitably inclined to obtain the most favorable operating conditions.

Although this indicator device is preferably mounted on the top of the headlight, it is evident that, to suit local conditions, it may be mounted in any angular position, without in any way affecting its operation.

As will be understood, as suggested herein, there may be slight changes made in the construction and arrangement of the details of my invention without departing from the field and scope of the same, and I intend to include all such variations, as fall within the scope of the appended claims, in this application in which the preferred forms only of my invention are disclosed.

I claim:

1. In an indicator device for a headlight, a reflector element made of flexible material and adapted to intercept light-rays from said headlight and reflect them rearwardly, an apron formed integrally with the reflector; an indicator lens positioned on the apron in the path of the reflected rays; a tubular support for said lens inserted through the apron and secured thereto, said tubular support having at its upper inner end a cutaway portion, and means to secure said device on the headlight.

2. In an indicator device for a head-light, a reflector element adapted to intercept light rays from said head-light and reflect them rearwardly; an apron supporting said reflector-element; a cylindrical tubular element mounted normally on said apron; an indicator-lens positioned in the tubular element and in the path of the reflected rays; said apron being made of bendable material for the purpose of varying the angular relation between the horizontal axis of the head-light and the tubular element, said tubular element having at its upper inner end a cut-away portion, and adjustable means to secure said device on a head-light.

In testimony whereof, I affix my signature.

EDWARD A. NIELE.
